CLAIM

The ornamental design for a landscape edging unit, as shown and described.

DESCRIPTION

FIG. 1 is a front perspective of a first embodiment of a landscape edging unit of the present design;

FIG. 2 is a front elevation thereof;

FIG. 3 is a top plan view thereof;

FIG. 4 is a back elevation thereof;

FIG. 5 is bottom plan view thereof;

FIG. 6 is a right elevation view thereof;

FIG. 7 is a left elevation view thereof; and,

FIG. 8 is a cross section taken in the plane of the line indicated in FIG. 7, wherein a cross section through the same plane looking in the opposite direction is a mirror image of FIG. 8.

1 Claim, 7 Drawing Sheets
